UNITED STATES PATENT OFFICE.

EPHRAIM K. HUTCHISON, OF DENVER, COLORADO.

AUTOMATIC DRAFT-REGULATOR FOR STEAM-BOILERS.

SPECIFICATION forming part of Letters Patent No. 597,375, dated January 11, 1898.

Application filed June 11, 1896. Serial No. 595,135. (No model.)

To all whom it may concern:

Be it known that I, EPHRAIM K. HUTCHISON, a citizen of the United States, residing at Denver, in the county of Arapahoe and State of Colorado, have invented certain new and useful Improvements in Automatic Draft-Regulators for Steam-Boilers; and I do hereby declare the following to be a full, clear, and exact description of the invention, such as will enable others skilled in the art to which it appertains to make and use the same.

This invention relates to automatic draft-regulators for steam-boiler furnaces.

My object is to provide a draft-regulator of the class described which will more perfectly perform its functions by promptly responding to abnormal variations in pressure and immediately rectifying them, thereby saving the fireman much time and labor.

Having this object in view, the invention consists of certain improved features and novel combinations, as will appear more fully hereinafter.

In the accompanying drawings, Figure 1 is a side elevation of my complete invention; Fig. 2, a plan view thereof; Fig. 3, a longitudinal section; Fig. 4, a side elevation of a boiler, showing the application of the device; Fig. 5, a cross-section taken through the low-pressure valve, and Fig. 6 a similar view taken in front of a certain plunger.

a designates the casing or housing, which is provided with suitable brackets 1 and 2, by which the regulator may be secured in position. This casing is divided into three cylindrical compartments or chambers 3, 4, and 5, respectively, and is provided with a suitable gland 6 at one end thereof. The chambers 3 and 5 are steam-chambers, while that designated 4 is not. Chamber 3 is provided with admission and exhaust ports 7 and 8, respectively, that communicate with chamber 5. The lower steam-chamber 5 has three drain-pipes 9, 10, and 11, respectively, which afford exhausts for the condensed or dead steam which would otherwise accumulate in the device.

A main piston 12, adapted for reciprocation in steam-chamber 3, is carried on the end of a piston-rod 13. The free extremity of this rod is provided with a coupling-head 14, adapted for connection with the "butterfly-damper"

15 in the smoke-stack 16 by means of a pitman 17. This piston-rod moves through a partition 18, provided with a suitable stuffing-box, and carries two limiting-plungers 19 and 20, the former of which slides on a guide 21, which is provided with a limiting-abutment 22.

The piston-rod 23, working in the lower steam-chamber 5, carries three auxiliary pistons 24, 25, and 26 and a releasing-plunger 27, which is provided with a stop 28, working in a slot in the partition between chambers 4 and 5, and has a lower upwardly-inclined face 29, being slotted longitudinally to provide arms 29^a. The piston 26 is somewhat larger than pistons 24 and 25, while piston 24 is provided with an exhaust-port 30, used to admit any existing steam to both faces of said piston 70 and keep the same in equilibrium.

The numeral 31 designates a collar suitably secured within the chamber 5, and 31^a a coil-spring interposed between said collar and piston 26. The normal tendency of this spring 75 is to keep the pistons pushed toward the left. The left extremity of piston-rod 23 is provided with an inclined abutment-face 32.

The numeral 33 designates the head of a plunger, which has an inclined abutment-face 80 34, on which the plunger 20 is adapted to ride, and is provided with a circular stem 35, having a port 36, and encircled by a spring 37, which tends to keep the plunger normally raised to prevent movement of plunger 20. 85 The plunger 33 is straddled by arms 29^a and is provided with trunnions 38, which press against the inclined faces 29 of the arms. The port in stem 35 permits any useless water or steam existing to pass out through the 90 drain 11.

The low-pressure valve operates in a cylinder 39 and the high-pressure valve in a cylinder 40. These two cylinders are joined by a pipe 41, which is in communication with 95 the delivery-pipe 42, that leads to the boiler. The low-pressure cylinder is connected to the steam-chamber 5 by a pipe 43, that leads to the space between pistons 25 and 26. The high-pressure cylinder 40 is connected to the 100 casing a by a hollow coupling 44, that affords communication between the cylinder and the steam-chamber 5. The rear face of this cylinder is connected to a vertical delivery-pipe

45, which communicates with the left end of the steam-chamber 3 by a delivery-port 46. The low and high pressure valves 47 and 48 are provided with stems 49 and 50, which are encircled by coil-springs 51 and 52, that are supported on adjustable followers 53 and 54, that are screwed into double removable caps 55 and 56 and through which the stems pass.

Assuming that the boiler is designed to carry one hundred pounds pressure, it would be desirable to set the low-pressure valve at ninety-five pounds and the high-pressure valve at one hundred and five pounds, although it is evident that the valves may be adjusted to open at any preferred pressure. The low-pressure valve is adapted to open the pipe 43 when lifted, while the high-pressure valve opens pipe 45. The tension on both of these valves may be regulated by turning the plunger 53 or 54 by a suitable key.

The numeral 57 designates a short pivoted trip-lever provided with an inclined abutment-face 58, adapted for engagement with abutment-face 32 and having one end projecting into a notch 59 in the valve 48. When the two abutment-faces come in contact, the high-pressure valve is lifted.

At 60 there is shown a closure which fits in and forms part of the casing *a*. This is immediately above the partition 18, and it can be removed to allow access to the stuffing-box in said partition.

In the use of the term "high pressure" as applied to the valve 48 I am to be understood as meaning a valve which is adapted to withstand a greater amount of pressure than the valve 47, as said valve 48 is operated by the auxiliary piston.

The invention operates in the following manner: I have assumed that the boiler, the draft of which is governed by my regulator, is designed to "blow" at a pressure of one hundred pounds per square inch, in which case the low-pressure valve is adapted to lift at ninety-five pounds and the high-pressure valve at one hundred and five pounds. Let it be further assumed that the butterfly-damper is open. (See Fig. 4.) The engagement of the plunger 19 with the lug 28 tends to keep the piston-rod 23 drawn toward the right and out of engagement with trip-lever 57, so that valve 48 is seated. When the pressure rises above ninety-five pounds, the low-pressure valve lifts, admitting steam through pipe 43 to the space between pistons 25 and 26. The latter piston being sufficiently larger in area than the former, the steam presses the piston-rod 23 toward the right. As the piston-rod 23 moves the plunger 27 depresses the vertically-operating plunger 32 and the piston 26 immediately after opens port 7, allowing the steam to press on the main piston 12 and force it to the left end of its chamber, closing the damper. The draft being shut off, the steam-pressure decreases, allowing spring 31 to force the piston-rod 23 toward the left, thereby engaging with

lever 57 and lifting the main pressure-valve 48. The exhaust-port 8 is also closed by piston 24. The condensed steam in chamber 5 passes out through the drain-pipes. When the main pressure-valve lifts, steam is again admitted to the left end of chamber 3 and the main piston forced toward the right, again opening the damper. Just prior to the piston 12 reaching port 7 (through which pipe 10 the dead steam in chamber 3 exhausts) plunger 20 rides on plunger 33, depressing and passing the latter. Said plunger 33 then locks plunger 20. Immediately afterward plunger 19 engages with stop 28, thereby disengaging trip-lever 57 and allowing valve 48 to reseat itself. When the steam-pressure again rises above ninety-five pounds, the operation is repeated.

The fluctuations in steam-pressure are thus automatically controlled and the best results attained.

Having thus described the invention, what is claimed as new is—

1. In an automatic draft-regulator, the combination with a steam-generator, of a draft-damper, a main cylinder, a main piston operating in said cylinder and operatively connected to the damper, an auxiliary cylinder, an auxiliary piston operating in said cylinder, a high-pressure valve governing the flow of steam from the generator to the main cylinder, a low-pressure valve governing the flow of steam between the generator and the auxiliary cylinder, a steam connection to the main cylinder which is governed by the auxiliary piston, and mechanism operated by the auxiliary piston which is adapted to actuate the high-pressure valve.

2. In an automatic draft-regulator, the combination with a casing or housing provided with main and auxiliary steam-chambers and provided with a port which connects one end of the main steam-chamber with the auxiliary chamber, of a main piston movable in the main chamber and adapted for actuating a damper, an auxiliary piston movable in the auxiliary chamber, means adapted to actuate the auxiliary piston to prevent admission of steam through the port, a high-pressure valve adapted for actuation by the movement of the auxiliary piston to admit steam to the piston end of the main chamber, a low-pressure valve which is adapted to admit steam to the auxiliary chamber, and means normally adapted to prevent actuation of the high-pressure valve by the auxiliary piston, substantially as described.

3. In an automatic draft-regulator, the combination with a casing or housing provided with main and auxiliary steam-chambers and having a port leading from one end of the main steam-chamber to the auxiliary chamber, of a main piston movable in the main chamber and adapted for actuating a damper, an auxiliary piston movable in the auxiliary chamber, a spring urging said auxiliary piston so as to normally prevent access of steam

through the port to the main chamber, means actuated by the main piston to lock the auxiliary piston, a high-pressure valve adapted to admit steam to the main chamber, and a low-pressure valve adapted to admit steam to the auxiliary chamber, the aforesaid auxiliary piston being adapted for engagement with the high-pressure valve to unseat the same when said auxiliary piston is disengaged by the movement of the main piston, substantially as described.

4. In an automatic draft-regulator, the combination with a casing provided with main and auxiliary steam-chambers which are in communication, of a main piston movable in the main chamber, a plunger connected to said main piston, an auxiliary piston movable in the auxiliary chamber and adapted to govern the flow of steam between the two said chambers, a piston-rod connected to said auxiliary piston and which has a stop adapted for engagement with the aforesaid plunger, a spring urging the auxiliary piston, a high-pressure valve adapted to admit steam to the main chamber, a low-pressure valve adapted to admit steam to the auxiliary chamber, and

means actuated by the movement of the auxiliary piston to unseat the high-pressure valve.

5. In an automatic draft-regulator, the combination with a casing or housing provided with main and auxiliary steam-chambers, of a main piston movable in the main chamber, a piston-rod for said piston, a plunger carried by the piston-rod, the latter being adapted to actuate a damper, an auxiliary piston movable in the auxiliary chamber, a piston-rod therefor, a releasing-plunger carried by the latter piston, a second and spring-compressed plunger retracted by the movement of the releasing-plunger and adapted to engage with the first named plunger, and means actuated by the movement of the auxiliary piston, whereby steam is admitted alternately on opposite sides of the main piston, substantially as described. 45

In testimony whereof I have signed this specification in the presence of two subscribing witnesses.
